UNITED STATES PATENT OFFICE.

CHARLES R. HARRIS, OF WILLIAMSPORT, PENNSYLVANIA.

DESIGN FOR A BUCKLE-FRAME.

SPECIFICATION forming part of Design No. 25,094, dated January 28, 1896.

Application filed April 22, 1893. Serial No. 471,513. Term of patent 14 years.

To all whom it may concern:

Be it known that I, CHARLES R. HARRIS, a citizen of the United States, residing at Williamsport, in the county of Lycoming and State of Pennsylvania, have invented and produced a new and original Design for Suspender-Buckle Frames, of which the following is a specification, reference being had to the accompanying drawing, showing a part thereof.

The accompanying drawing is a front elevation of my buckle-frame.

The leading feature of my design consists of a frame of wire bent to form top, bottom and side bars, an approximately centrally-located cross-bar formed by parallel inward and outward bends of the wire of each side bar toward each other, and a front bar extending centrally from the top of the frame to the bottom approximately at right angles to the centrally-located cross-bar.

A represents the top, B, the bottom, and C

C the side bars of the frame. A portion of the wire from each side bar is bent inward, as at D, toward each other and then outward, as at E, so that the parts D and E are parallel, or approximately so, and when thus formed constitute in effect a single cross-bar. A front bar, G, extends downward from the top bar to the bottom bar of the frame, crossing the cross-bar where the ends of the latter approach other. Thus the entire frame is rectangular in shape and has a cross-shaped figure therein.

Having fully described my design, what I claim as new, and desire to secure by Letters Patent, is—

The design for a buckle-frame herein shown and described.

CHAS. R. HARRIS.
